UNITED STATES PATENT OFFICE.

GEORGE WASHINGTON TRAHAN AND TELESPHORE BABIN, OF HOUMA,
LOUISIANA.

VOTING-MACHINE.

SPECIFICATION forming part of Letters Patent No. 398,196, dated February 19, 1889.

Application filed September 22, 1888. Serial No. 286,069. (No model.)

To all whom it may concern:

Be it known that we, GEORGE WASHINGTON TRAHAN and TELESPHORE BABIN, both residents of Houma, in the parish of Terre Bonne 5 and State of Louisiana, have invented certain new and useful Improvements in Registers for Ballot-Boxes, Tills, &c.; and we do hereby declare that the following is a full, clear, and exact description of the invention, which will 10 enable others skilled in the art to which it app pertains to make and use the same, reference being had to the accompanying drawings, which form a part of this specification, and in which—

15 Figure 1 is a top plan view of my register for ballot-boxes, money-tills, &c., showing the cover thrown back. Fig. 1^a is a top plan view of the lid, showing its peculiar construction. Fig. 2 is a transverse section. Fig. 3 is a longitudinal vertical sectional view. Fig. 4 is a plan view of the upper section, showing the registering-wheels and appliances removed; and Fig. 5 is a top plan view of the side apartment, showing a modification in the arrangement of the numbers upon the dials, illustrating 20 how the device may be employed more particularly as a money-till.

Like letters of reference denote corresponding parts in all the figures.

25 Our invention has relation to a device for registering the votes deposited in ballot-boxes, also to be used as a register for money-tills, fare-boxes, in places of amusement, and for a variety of different purposes, and is designed 30 to guard against the improper placing of tickets in the box, consisting in the improved construction and combination of parts of the same, as hereinafter more fully described and set forth.

40 In the accompanying drawings, the letter A indicates the outer casing, provided with a suitable cover, B. Hinged within this outer casing is a tray, C, resting upon corner-pieces D in said casing. This tray C is provided with 45 a division or apartment, E, said apartment having hinged thereto a lid, F, which is provided with holes G G, said holes having pivoted above the same lids or covers H H, designed to cover or uncover the holes when desired.

50 A deposit opening or hole, I, is located in

the tray C, and has extending from the under side thereof a guard, J, the front portion of said guard being partly cylindrical. A deposit lid or plate, K, is rigidly mounted upon a shaft, L, above this deposit-opening, the rear portion of said lid being curved upward to afford a ready grasp for the hand. One end of this shaft L is journaled in a bearing, M, to one side of the opening, while the other passes through the side of the apartment E, where it is provided with a crank, N, which is engaged by a spring, O, one end of said spring being secured in any desired manner to the bottom of the apartment. The shaft 65 then continues transversely across, being held in place by suitable keepers or bearings, P, and is provided on its extreme end with a crank, Q, which engages and actuates a flat plate or bar, R, said bar passing through 70 sleeves S and T, located upon the side of the apartment E. Secured to the sliding plate R and the sleeve T, respectively, are spring-pawls U and V. A flat spring, W, is also secured to the bottom of the apartment E, the 75 end thereof bearing against one end of the sliding plate R, which, together with the spring O, serves to turn the shaft back to its original position after the deposit-lid has been raised and the ticket deposited.

80 Toothed dial-wheels X and Y turn in bearing in the bottom of apartment E, wheel X being located beneath wheel Y and numbered at regular intervals from 1 to 100. Wheel Y is numbered at regular intervals of one hundred—as, for instance, one hundred, two hundred, three hundred, and so on, to ten thousand—the difference between the interval of each being one hundred. As the deposit-lid is pressed inward in order to deposit the vote 85 or ticket, the shaft is turned, and with the turning of said shaft the flat plate or bar R is moved within the sleeves S and T. As this bar R is moved, it carries with it the spring-pawl U, rigidly secured thereto, said pawl engaging the teeth of the wheel X and turning it one notch, the second spring-pawl, V, secured to the sleeve T, likewise engaging one of the rear notches and preventing the dial 90 from turning back.

95 Secured to the dial X is an eccentric-pin, Z, which, when said dial X has made a com-

plete revolution, will engage the teeth of dial Y and move it one notch, a spring-pawl, A', located upon the inner side of the apartment E, also engaging the teeth of the dial, and 5 overcoming any tendency which the same may have to slip back.

If desired, the apartment E may also be provided with cross-strips B' B', upon which the rims of the dials may be supported.

10 Above the dial X is a slotted plate, C', partly circular in shape, to conform to the contour of said dial, and having extended ends, soldered or otherwise secured to the sides of the apartment. By the arrangement of this slotted plate the number of votes deposited is 15 easily discernible. A like slotted plate, D', is arranged above the dial Y and answers a similar purpose.

The above being a description of our invention, its operation is as follows: In the first 20 place, the dials X and Y are set, respectively, at numbers 100 and 10,000, and the lids or covers above holes G G are closed. The vote, ticket, or fare is deposited upon the deposit-lid and the same pressed inward. After the lid reaches a point beyond the end of the curved portion of the under guard the pawl U acts upon the teeth of the dial X and turns it from 1 to 2, and so on, registering each 25 vote as it is placed upon the deposit-lid and carried within the space of casing A. When the dial X has made a complete revolution, the eccentric-pin will engage the teeth of dial Y and will turn it from 10,000 to 100. It will 30 thus be seen that the dial Y will always tally the number of hundred votes cast, and should the voting cease upon the fractional part of a hundred the dial X will indicate that fractional part.

35 It is of course desirable to keep the lids above holes G G closed until it is found necessary to ascertain the number of votes deposited, when said holes may readily be uncovered and the exact number of votes determined.

40 If desired, the guard J may be provided with a bell, E', provided with a trip adapted to be engaged by the end of the deposit-lid when the same is pressed in, so that as each 45 vote is deposited the bell will be sounded, indicating that the vote has been properly registered.

45 It is obvious that as many of these registering-dials as may be found desirable may be employed, so that the capacity of the device to register votes will be almost unlimited. By the employment of the two dials, as shown in the drawings, the device will register from one to ten thousand votes, three 55 dials from one to one million, and so on indefinitely. The device, moreover, is little liable to get out of order, is simple in construction, comparatively inexpensive of production, and absolutely correct in registering, 60 the device being operated only by the person making the deposit.

In Fig. 5 of the drawings we have shown the device as adapted particularly for money-tills.

Upon the under wheel the numerals are arranged in regular order from 1 to 19, and following 9 two ciphers (00.) Each one of these numerals represents five cents, so that there is a total of twenty five-cent pieces or nickels indicated upon the dial, or \$1.00. 70

Upon the upper dial the numbers are arranged at regular intervals from \$1.00 to \$100, there being a difference of one hundred points between each numeral. The under dial is of course provided with an eccentric-pin, so that when it makes one complete revolution, or reaches the point 00, the upper dial will indicate \$1.00, two revolutions \$2.00, and so on. 80

Instead of the under dial being arranged 85 with numerals from 1 to 00, as above described, the twenty spaces may be numbered from 5 to 100, there being a difference of five between said spaces, so that the total indicated will be \$1.00 or twenty nickels—that is 90 to say, the spaces will run 5, 10, 20, &c., until 95 is reached, the next space being 00, at which point the upper wheel will be revolved, indicating \$1.00.

This system of registering money, it is obvious, can be carried indefinitely. For instance, it may be arranged as a ten cents register, twenty-five cents, fifty cents, one dollar, two dollar, &c., by simply varying the arrangement of the numbers on the dial on the 100 same principle as before explained.

In order to facilitate the setting of the dials, we also prefer to provide each with a central pin or pivot, F', which is adapted to receive a key, thus enabling the dials to be turned 105 without difficulty.

Having thus described our invention, we claim and desire to secure by Letters Patent of the United States—

1. In a registering device for ballot-boxes, 110 &c., the combination, with the outer box or casing, of the inner tray provided with a suitable deposit-opening, the deposit-lid above said opening having a shaft rigidly secured thereto, and the toothed registering mechanism mounted in suitable bearings in the bottom of the tray actuated by said shaft, substantially as set forth. 115

2. The combination of the outer casing having inner corner-pieces, the hinged inner tray provided with a deposit-opening, the deposit-lid having a transverse shaft rigidly secured thereto, said shaft being provided with cranks, the side apartment, the spring adapted to engage the innermost of said cranks, the sliding plate or bar having a spring-pawl secured thereto, the sleeves in which this sliding bar moves, one of said sleeves having a spring-pawl secured thereto, the toothed registering-dials mounted in suitable bearings in the bottom of the apartment, one of said dials being provided with an eccentric-pin, and the spring- 120 125 130 135

pawl adapted to engage the teeth of the rear-most registering-dial, substantially as set forth.

3. The combination of the outer casing having inner corner-pieces, the hinged inner tray provided with a deposit-opening, the guard located beneath said opening and provided with an alarm-bell, the deposit-lid having a transverse shaft rigidly secured thereto, said shaft being provided with cranks, the side apartment, the spring adapted to engage the innermost of the cranks upon the shaft, the sliding plate or bar having a spring-pawl secured thereto, the sleeves in which this sliding bar moves, one of said sleeves being provided with a spring-pawl, the toothed registering-dials mounted in suitable bearings in the bottom of the apartment, one of said dials being provided with an eccentric-pin, and the spring-pawl adapted to engage the teeth of the rearmost registering-dial, substantially as set forth.

4. The combination of the outer casing having inner corner-plates, the hinged inner tray provided with a deposit-opening, the deposit-lid having a transverse shaft rigidly secured thereto, said shaft being provided with cranks, the side apartment, the spring adapted to engage the innermost of said cranks, the sliding plate or bar having a spring-pawl secured thereto, the sleeves in which this sliding bar moves, one of said sleeves having a spring-pawl secured thereto, the flat spring adapted to engage the forward end of said sliding plate or bar, the toothed registering-dials mounted in suitable bearings in the bottom of the apartment, one of said dials being provided with an eccentric-pin, the slotted curved plates having the slits therein registering with the openings in the cover of the side apartment, and the spring-pawl adapted to engage the teeth of the rearmost toothed dial, substantially as set forth.

an eccentric-pin, and the spring-pawl adapted to engage the rearmost registering-dial, substantially as set forth.

5. The combination of the outer casing having inner corner-pieces, the hinged inner tray provided with a deposit-opening, the guard located beneath said opening and provided with an alarm-bell, the deposit-lid having a transverse shaft rigidly secured thereto, said shaft being provided with cranks, the side apartment having a hinged cover, said cover being provided with suitable openings having pivoted covers above the same, the spring adapted to engage the innermost of the cranks located upon the transverse shaft, the sliding plate or bar having a spring-pawl secured thereto, the sleeves in which this sliding bar moves, one of said sleeves being provided with a spring-pawl, the flat spring adapted to engage the forward end of said sliding plate or bar, the toothed registering-dials mounted in suitable bearings in the bottom of the apartment, one of said dials being provided with an eccentric-pin, the slotted curved plates having the slits therein registering with the openings in the cover of the side apartment, and the spring-pawl adapted to engage the teeth of the rearmost toothed dial, substantially as set forth.

In testimony that we claim the foregoing as our own we have hereunto affixed our signatures in presence of two witnesses.
